UNITED STATES PATENT OFFICE.

HECTOR FALLETTA, OF LOS ANGELES, CALIFORNIA.

DRAFTING IMPLEMENT.

Application filed May 7, 1927. Serial No. 189,716.

This invention relates to improvements in drafting implements and appliances and more particularly to compasses and has for its object to provide a simple, efficient and inexpensive device of this character.

One of the objects of my invention is to provide a drafting appliance designed to effect the ruling of parallel lines for musical notation, lettering in connection with drawings or for any other purpose.

Another object of my invention is to provide improved means for ruling parallel lines by means of a compass or dividers means being provided for varying the spacing of the parallel lines drawn.

A still further object of my invention is to provide, in a compass having means for ruling parallel lines, means for gauging the spaces between the ruled parallel lines for the purpose of providing uniform margins or spaces between the several sets of parallel lines.

Another object of my invention is to provide an attachment to compasses to be associated with the pencil point thereof designed to line the pencil point against the edge of a ruler against which the pencil point is drawn to mark out a rectilinear outline on paper.

And a still further object of my invention is to provide an attachment for compasses provided with pencil points for ruling or tracing parallel lines characterized by the feature that an extended bearing surface is presented against the edge of the ruling and the pencil point itself made to follow its rectilinear course without directly contacting the ruler edge.

In carrying out the purposes of my invention I provide a drafting implement with a bifurcated leg, so that this leg has two laterally adjustable branches and, a pencil point designed to be mounted in each separate branch; means are also provided for separating the branches different distances to determine how far apart the parallel lines shall be ruled or drawn.

With the above and other objects in view my invention consists in the combination, arrangement and details of construction disclosed in the drawings and specification, and then more particularly pointed out in the appended claims.

In the drawings, wherein similar reference characters designate similar parts throughout the respective views,

Figure 1 is a perspective view of my invention;

Figure 2 is an end elevation of my invention, partly in section,

Figure 3 is a top plan view of my invention, 60

Figure 4 is a bottom plan view of my invention,

Figure 5 is a diagrammatic view of the work done by my invention,

Figure 6 is a rear end elevation of my invention, 65

Figure 7 is a fragmental detail perspective view of the blade attachment of my device, and

Figure 8 is a front elevation of my invention. 70

Referring to the drawings, which are merely illustrative of my invention a compass is shown consisting of the handle or shank 10, having the annular flange 11 formed with a stub 12 provided with the oppositely and downwardly extending legs 13 and 16 which are formed resilient so as to be laterally yieldable as well as adjustable. The lower portion 14 of the leg 13 terminates in a prong 15, while the leg 16 has a bifurcated portion. 80 Both legs 13 and 16 come together in an arch at the upper end of the implement.

The bifurcated portion of the leg 16 consists of the substantially parallel branches or arms 17 and 18 which are also formed resilient 85 so as to be laterally yieldable and adjustable. At the lower ends or extremities of the arms 17 and 18 pencil points or pen points 18 and 19 project, and are retained in these arms in hollow compartments (not shown) and of a 90 form well known to those skilled in the art of compass construction. It may be desirable to provide a spring mounting for said pencils so that upon severe pressure the pencil points may yield by moving upwardly in the arms. 95

As a means of laterally adjusting or separating the legs as between themselves or the arms as between themselves, a screw bolt 24 is arranged to connect with these arms and leg as follows: this bolt is screw threaded for the greater portion of its length and one end is secured to the arm 18 of the bifurcated portion of the compass so as to swivel therein without movement in the direction of its own axis. 100

This screw bolt 24 is also threaded into the arm 17 of the bifurcated portion of leg 18, and thence it extends across so as to span leg 13 and arm 17, being threaded thru leg 13 and projecting therebeyond, and at its 110

free end this screw bolt 24 carries a knurled head or flange 27 by means of which it may be rotated. A knurled collar 26 is also threaded upon screw bolt 24 and is stationed between 5 leg 13 and head 27; another similar collar 25 is screw threaded upon bolt 24 so as to bear against arm 17 and be located between arm 17 and leg 13.

It will be readily seen that when the screw 10 bolt 24 is rotated both arms and the leg 13 may be caused to separate or to approach; but I prefer that the screw bolt 24 project thru unthreaded openings in the arms and legs of the compass, so that the collars 25, 26 15 may be the actuating means for separating the arms or the legs. Thus by rotating the collar 25 the arms 17, 18 may be brought together; similarly by rotating collar 26 the legs may be brought together.

20 A most important feature of my invention relates to means serving as a straight edge against which to line a ruler for the purpose of causing lines to be drawn parallel to the ruler. The sheet metal guard or flat blade 25 21 is provided and disposed in an upright position closely adjacent pencil point 19, its upper end taking the form of a lug 20 operatively secured to the arm 18. Inscribed upon one side of this blade is a mark 23.

30 When now it is desired to rule parallel lines the two pencil points 18 and 19 will be drawn forcibly across the sheet of paper A producing the parallel lines 30 shown in Figure 5; if it is desired to gauge the distance apart between sets of parallel lines 30, all it is necessary to do is to set the leg 13 relatively to the bifurcated leg 16 by operating the threaded collar 26 which screws upon screw bolt 24; thus leg 13 can be flexed 35 inwardly or outwardly; the distance between the prong 15 and pencil point 18 defines the space 32 between the sets of parallel lines 5; and of course this space will be uniform, so the sets of parallel lines will be spaced uniform 40 distances apart.

In order to position a ruler upon the working sheet in a manner to rule parallel lines properly, I have devised the blade 21 to act, in conjunction with point or spur 15, as a 50 gauge; instead of employing a ruler to provide the initial line to be paralleled I employ the blade 21 in a manner to set the ruler itself in position on the sheet to set apart parallel lines.

55 In practice the calibration mark 23 on blade 21 will be brought into registration with mark 23 on the sheet A, if this latter mark is known to be parallel to the edge of the sheet; otherwise the spur 15 of the compass will be pushed into the edge C of the sheet, while the calibration mark 22 of blade 21 will be caused to register with this same edge C; this having been done, and while the blade is still in the last named position, 60 a ruler D is taken and presented with its

straight edge against the blade 21. Next hold the ruler against movement and draw the device across the sheet and as the two pencil points 18 and 19 will touch the paper the same time the blade 21 does, these points 70 will now trace two lines which will be exactly parallel with the edge C of this sheet. In this manner it is assured that the initial line will be parallel with the edge of the sheet, and therefore every other lines and 75 sets of parallel lines will be parallel.

I do not mean to limit myself to the exact details of construction herein disclosed but intend to cover all variations and changes set forth in the appended claims. 80

What I desire to protect and seek by Letters Patent is:—

1. A device as described consisting of a shank having two legs, one of which is forked at its lower extremity to rule parallel lines, 85 and means for adjustably controlling the separation of the legs.

2. A device as described consisting of a shank having two legs resiliently mounted of which one leg is forked, a pointed prong formed upon the free end of the other leg, 90 means carrying lead points at the free ends of the members of the forked leg, and means carried by the forked leg and engaging adjustably the other leg for varying the distance apart between the legs. 95

3. A device as described consisting of a shank, a pair of resilient legs yieldably mounted upon said shank, a pointed prong carried by one of said legs, a pair of yieldably separable stems carried by the other leg, pencil points carried removably by said stems designed to rule parallel lines, means for varying the distance apart of said stems, and means for varying the distance apart between said set of stems and said pointed prong. 100

4. A device as described consisting of a compass equipped with a bifurcated leg, means for holding pencil points at the lower extremities of the branches of said bifurcated leg, for ruling parallel lines, and guide means carried by said bifurcated leg for abutment against a straight edge whereby said pencil points may be used for scribing parallel lines. 105

5. A device as described consisting of a compass having a pointed leg and a lead carrying bifurcated leg, means for controlling the separation of said legs, and a flat blade carried by one bifurcation of the bifurcated leg and designed for slidably engaging a ruler to prevent rotation of the bifurcated leg during a drawing of parallel lines. 110

6. A compass having one leg provided with a pencil point and with a flat blade disposed laterally of the pencil point, and serving to guide a pencil point as it slides against the straight edge of a ruler. 115

In witness whereof he has hereunto set his hand this tenth day of March, 1927.

HECTOR FALLETTA.
